UNITED STATES PATENT OFFICE

104,004

DESIGN FOR A MERCHANTISE DISPLAY STAND

James F. Urbanek, Elmwood Park, Ill., assignor
to The Susu Nut Co., Chicago, Ill., a corporation
of Illinois

Application August 29, 1936, Serial No. 64,633

Term of patent 14 years

To all whom it may concern:

Be it known that I, James F. Urbanek, a citizen of the United States, residing in Elmwood Park, in the county of Cook and State of Illinois, have invented a new, original, and ornamental Design for a Merchandise Display Stand, of which the following is a specification, reference being had to the accompanying drawing, forming a part thereof.

In the drawing:

Fig. 1 is a perspective view of a merchandise display stand showing my new design, and

Fig. 2 is a plan view of the upper portion of the article shown in Fig. 1.

My design is characterized by a plurality of superimposed generally tubular supporting members of successively smaller cross section on which the articles to be displayed are carried.

I claim:

The ornamental design for a merchandise display stand substantially as shown and described.

JAMES F. URBANEK.
